CLAIM

The ornamental design for sample cup, as shown and described.

DESCRIPTION

FIG. 1 is a top view of a sample cup.

FIG. 2 is a front view of the sample cup.

FIG. 3 is a right side view of the sample cup.

FIG. 4 is a left side of the sample cup.

FIG. 5 is a bottom view of the sample cup.

FIG. 6 is a back view of the sample cup; and,

FIG. 7 is a perspective view of the sample cup.

The broken lines are included for the purpose of illustrating unclaimed portions of the sample cup and form no part of the claimed design.

1 Claim, 4 Drawing Sheets
